RATION OF KENTUCKY.

APPARATUS FOR DISTILLATION.

1,379,876.

Specification of Letters Patent. Patented May 31, 1921.

Application filed May 16, 1919. Serial No. 297,502.

To all whom it may concern:

Be it known that we, CARL A. NOTTINGHAM and CARL TUHEY, citizens of the United States, residing at Muncie, in the county of Delaware and State of Indiana, have invented certain new and useful Improvements in Apparatus for Distillation, of which the following is a specification.

This invention relates to improvements in apparatus for the destructive distillation of carbonaceous substances such as corn-cobs or analogous ligneous materials.

We are aware that many inventions in methods and apparatus for destructive distillation of wood and like substances have heretofore been patented, but we are not aware that any apparatus has been devised for the distillation of corn-cobs.

By reason of the comparatively low moisture contents of corn-cobs and of their peculiar composition and structure, as distinguished from wood and other ligneous materials, the present invention proceeds along certain lines in conformity with the nature and peculiarities of said material.

The objects of the invention are to provide an apparatus for the continuous destructive distillation of corn-cobs in volume and quantity sufficient for the production of distillates in quantity to make profitable the practice of such distillation. Further purposes of the invention are to provide an apparatus by which the maximum quantity of distillates may be recovered at the minimum expenditure of time and expense.

The foregoing objects of our invention are accomplished by the mechanism embodying our invention and which comprises the several parts and combinations thereof described in this specification and illustrated in the accompanying drawings. The invention is defined in the appended claims.

In the drawings, the several parts of the invention are identified in the different views, by suitable characters of reference.

Figure 1 represents a central longitudinal vertical sectional view of our apparatus, parts thereof being shown in elevation.

Fig. 2 is a transverse sectional view taken on the line 2—2, and

Fig. 3 is a transverse sectional view taken on the line 3—3, in Fig. 1, and as seen in the direction indicated by the arrow.

Fig. 4 is a detached enlarged detail view

of the inlet valve and its connected parts, taken on the line 4—4 and seen in direction indicated by the arrow 4 in Fig. 1.

Fig. 5 is a detached detail view showing the meeting ends of the divided shaft of the conveyer that operates in the lower retort.

Fig. 6 is a detached view of suction producing means or a vacuum pump.

In the mechanism herein described, and which is adapted to the distillation of corn-cobs in large quantities, the apparatus comprises a pair of horizontal cylindrical retorts made preferably of sheet steel and having a diameter of about eight inches. The retort A, supported in the upper portion of a heating furnace presently to be described, is about twelve feet in length, the closed ends of same being provided with journal bearings A¹ and A². A similarly constructed retort B is disposed in alignment with and at spaced distance below the retort A, and it is provided at its closed ends with the journal bearings B¹ and B². At the forward end of retort A is arranged an upwardly directed sleeve A³ upon which is secured the valve casing C. A detail view of this valve casing and the valve mechanism therein, is seen in Fig. 4. This casing is of cast metal, and has the inlet port 15 and the discharge port 16. Secured on a shaft 17 that is journaled in the side walls of the said casing is a valve C¹ of the peculiar construction shown. This valve has its three similar arms spaced equidistant and they are of such length and their peripheral faces are of such curvature that they fit slidingly in the machined circular bore of the casing C. It is apparent that while both the inlet port 15 and the outlet port 16 are continuously open for the receiving and discharging of contents intended to pass through the said casing, the valve is at all times closed against escape through its ports of the volatile contents of the retort A. An additional function of the ends of the arms of the valve and which have the angular cutting edges C², is to cut or break the cob mass as the said edges pass the edge of the port 15.

A hopper D of suitable form and construction is arranged above the valve casing C so that its contents may flow directly into the port 15. Rising from the rearward por-

tion of the retort A is a conduit E. For the purpose of disposing this conduit at position so that free access may be had at the rearward end of the retort in the assembling of the parts hereinafter described, an elbow joint E¹ is provided and which extends at a right angle to said conduit. From this elbow joint E¹ the conduit E extends in a direction inclined downwardly thence to its 10 point of entrance into the receiving chamber to be presently described.

The forward end of retort B extends a short distance at its forward end beyond the end of the retort A and a substantial distance from the furnace. The resultant exposure of the walls of the retort B will lower the temperature of the treated material in the retort before it is discharged to contact with the air and lessen the tendency for it to 15 be burned when it is exposed to the air. A sleeve B³ is secured to its under side adjacent its end and the valve casing J is secured to this sleeve. A shaft 19 that is journaled in suitable bearings provided in the 20 sides of the said casing has secured thereon a valve J¹ of construction identical with that of the valve C¹, and which valve J¹ opens and closes ports 20 and 21, in a manner similar to the action of valve C¹ with 25 reference to ports 15 and 16. Openings A⁴ and B⁴ in the retort A and B, respectively, afford communication between said retorts and the said valve casings.

G designates a conduit which provides 30 communication between the retorts at their rearward portions through suitable openings therein. In the retort A is arranged a spiral conveyer F to drive contents to the rear of the retort, the ends of its shaft F¹ 35 being journaled in the journals A¹ and A². In the retort B is arranged a spiral conveyer H to drive the contents forwardly in the retort B, its shaft being of divided construction. The inner ends of the shaft sections H¹ and H² appear as shown in the detail view in Fig. 5. These shaft sections 40 which have their ends journaled in the bearings B¹ and B², as shown in Fig. 1, are actuated by suitable driving connections to be 45 presently described.

The retorts above described are contained in a masonry furnace K of structure and form substantially as shown, and which is provided with a horizontal partition 22 so 50 arranged that the heat (preferably generated from gas or petroleum) introduced into the forward portion of the chamber K¹ and directly underneath retort B, passes to the rear and up through opening K² and 55 into the chamber K³, the draft or vent for the furnace consisting of the chimney K⁴. By this arrangement, the maximum temperature of the furnace heat, is exerted at the frontal portion of the retort B, and the 60 gradually lessening temperature is exerted 65

toward the rear portion of retort B. The heat delivered into the chamber K³ of still lower temperature intensity, is of a continuing lower degree toward the frontal portion of retort A, so that while the cob mass as 70 introduced into the retort A is at first subjected to a comparatively low degree of heat, it is subjected to the maximum degree of heat as it reaches the end of its travel at the forward end of retort B. 75

Connections for the transmission of power from a driving shaft 24 that has the pulleys 25 and 26, may consist of belts 27 and 28 running over a pulley 29 that is secured on shaft F¹, and a slightly smaller pulley 30 80 that is secured on the shaft H², respectively. The diameter of the spiral conveyers F and H, is about six and one half inches, the inside diameter of the retorts being about eight inches. The pitch of the two said 85 spirals being opposed, it is apparent that although the conveyer shafts are rotated in the same direction, the conveyer F causes a shifting of the retort contents to the rear of the retort, and the conveyer H causes a 90 shifting of the contents of retort B forwardly. To provide against "warping" of the shaft of conveyer H, the shaft, as hereinbefore described, is made in two sections. To actuate the conveyer H most effectively, 95 the power of shaft section H² is transmitted to the shaft section H¹ by a link belt 31 running from pulley 32 of shaft H², over a pulley 33 of a shaft 34; and by a link belt 35 running from pulley 36 of shaft 34 over 100 pulley 37 that is secured to shaft H¹. The size and arrangement of these connections are such that the conveyer F is operated at a speed slightly less than that of the conveyer H. For the continuous rotation of the 105 valves C¹ and J¹ there may be arranged a belt 40 from a pulley 41 of driving shaft 24, to run over a pulley 42 that is secured on valve shaft 17. A belt 43 from a pulley 44 on shaft 17 running over a pulley 45 110 that is secured to shaft 19 causes the rotation of the valves C¹ and J¹. In the present arrangement these valves are operated at the same speed. 115

The valve C¹ operates in such manner that while permitting the cob-contents of the hopper D to flow freely, it permits only a determinate or definite quantity to enter the retort; thus assuring a uniformity of the flow or feed of the cob mass into the retort 120 A. Similarly, the valve J¹ operates to permit the discharge of the dry distillates from the retort B. The cobs being first denuded of the chaff, and having been reduced to sizable dimensions,—say,—to pieces an inch 125 to one and one half inches in length,—are delivered into the hopper D. The action of the valve C¹ is to cut and mangle the cob pieces as they pass through the port 15 and as the edge of the valve arm passes the edge 130

of the port 15, a quota of the cob mass is retained between the two arms of the valve, to be discharged through port 16, whence it falls into the retort A. This cob-mass, as it 5 proceeds in its travel toward the opening at conduit G, is so affected by the heat surrounding the retort, that it yields its volatile elements in the form of a vaporized mixture or gas of distillation.

10 It will be understood that by means of a vacuum pump of suitable capacity and which may be of type shown in Fig. 6 there is a free and continuous flow of the gases from the retorts through the conduits G and 15 E, the latter conduit having connection with the receiving chamber presently to be referred to. The said cob-mass, under the effect of said temperature and of the propulsion and churning by the conveyer, is moist 20 and pulpy as it travels to the opening at G where it falls into the rear portion of retort B. In the continued propulsion and churning of the mass and in its movement forward in the retort B it continues to yield 25 its volatile contents in the form of gases that are caused to pass upwardly through opening G and through the conduit E. The cob-mass as it reaches the forward portion of the retort B will have assumed the form of 30 charcoal. This charcoal is of the finest grade, being fluffy and free from moisture content. The action of the valve J¹ is to discharge this dry distillate through the port 21 into a suitable closed container 46 35 from which the charcoal may be taken into the open air after a proper length of time.

The furnace shown herein is arranged for the use of fuel gas introduced through openings K⁵ into the combustion chamber K¹. 40 Valve control means (not shown) render possible the regulation of the intensity of the heat flames at the burners 47, 48 and 49.

The gases passing through the conduit E are heavily laden with the volatile parts 45 yielded from the cob mass, and the purpose of the construction, combination and arrangement of parts now to be described, is to effect the condensation of said gases. We designate this construction as a receiving 50 chamber or housing for the several parts that constitute means the function of which is to cool and divide the gases into the condensable and non-condensable portions, and to reduce or break up into its constituent 55 elements, the condensable gases. In this part of the distillation, two crude products are obtained, namely; crude pyroligneous acid, and tar. A housing of A shape in cross section, consists of uprights L and L joined 60 at their tops by a longitudinal tie member L¹; these uprights may consist of boards of wood or composition, and secured on their inner sides are sheet metal plates L² and L³. These sheet metal plates are preferably of 65 copper as this metal withstands the effects

of the gases without corrosion. The lower edges of the uprights L and L rest on the top edges of the walls of the rectangular box-like container or tank L³, the bottom edges of the plates L² extending slightly 70 below the lower edges of the uprights. This construction makes a smooth and unobstructed surface for the distillates that meet the plates L². The temperature of these plates L² is maintained at a low degree by a 75 continuous flow of water that passes through perforations in the pipe L⁴.

This pipe L⁴ which is arranged directly above the member L¹ is provided with a suitable valve L⁵ by which the quantity flow 80 of water from the source of supply, may be regulated. It will be understood that at the ends of the housing plates L are similar transverse plates L⁶ that constitute a closed housing for the several parts constituting 85 the condensing means. At spaced distances apart longitudinally and extending transversely of the condenser plates L², are baffle plates L⁷, L⁸ and L⁹ arranged in the upright 90 positions as shown.

The gases entering through conduit E pass upwardly and over the top of plate L⁷ thence downwardly and below plate L⁸. The parts of the gases that are precipitated on the cold plates L² flow and drip readily 95 from the said plates into the water contained in the tank. This process of separation of the distillates from the gases is repeated as the gases proceed in their forced travel through the spaces or chambers between the several baffle plates; the distillates settling in the several compartments between the transverse plates L⁹ in the tank. These compartments are numbered 1 to 7 both inclusive. In this process of distillation all of the volatile distillates of the 100 gases will have been separated from the gas mass and settled in the compartments of the tank, the non-condensable gas of said gas-mass being conducted from the condenser through the pipe N whence it may be delivered to pipe lines for use as illuminating gas, or for any other commercial purpose desired. Water that is contained in the tank L³ has its level at the dotted line, 105 above the top edges of the baffle plates L⁹ and below the conduit E. The outlet pipe M is retained closed by a trap arrangement M¹. Carried in suspension in the water is 110

a crude pyroligneous acid that is taken off 115 through pipe M. The distillates found in the compartments comprise tar and creosote distillates ranging in consistency of varying thickness and texture; the distillates of the heavier specific gravity being found in the 120 compartments commencing with the compartment 1. At the bottom of each of the compartments are provided discharge pipes, each with a stop-cock P, through which the liquid distillates may be drawn off. 125 130

1. Through the pipe N is operated a suction produced by a suitable vacuum pump T which besides affording a continuous suction through the conduit E, draws from 5 the condenser, the non-condensable gases as above described.

The apparatus described has a capacity for handling a sufficient quantity of corn cobs within a given period of continuous 10 operation to afford results of decided commercial value. From the corn cob mass treated by our process of distillation in this apparatus there is yielded divers distillates, including charcoal.

15 While in this specification, we have shown our apparatus in the form as a separate unit, complete, and with capacity for continuous distillation of a certain quantity of corn-cob raw material; the invention is embodied in such manner that increased capacity may be developed by the arrangement of a series of the machines adapted to be actuated by a common means of power, and a common source of heat and suction.

20 25 While we have described our apparatus as peculiarly adapted for the destructive distillation of carbonaceous substances such as corn-cobs, or analogous ligneous materials, the same is applicable to the distillation of 30 other substances as, for example, oil bearing shales.

In showing our invention embodied in what we consider the preferred form of construction, combination and arrangement of 35 parts for carrying same into effect, we are aware that minor changes may be made in the detailing and arrangement and construction of the several parts, within the range and scope of the appended claims, 40 without departing from the spirit of the invention or sacrificing any of its advantages.

What we claim as our invention, and desire to secure by Letters Patent, is—

45 1. In an apparatus of the class described, in combination, a plurality of superposed retorts, inlet and discharge means at alternate ends of said retorts, means in the first inlet and in the last discharge means to 50 pass material while preventing the passage of gaseous currents, the intermediate discharge and inlet means providing communication between retorts, means to subject said retorts throughout the entire extent of 55 their heated portions to temperatures gradually increasing from a point adjacent the first inlet to a point adjacent the final discharge means, conveying means adapted to convey and agitate material from the inlet 60 to the discharge means of each retort and an outlet for the distilled product.

65 2. In an apparatus of the class described, in combination, a furnace, a pair of superposed retorts extending within and projecting from the front end of said furnace, inlet

and discharge means communicating with the projecting ends of said retorts, the discharge end of the lower retort projecting a substantial distance from said furnace whereby to cool material therein before discharge therefrom, means to allow material to pass from the upper to the lower retort within the furnace, a baffle within the furnace between the retorts extending rearwardly from the front end and ending short 70 of the rear end thereof, means to apply heat to the lower retort at the forward end of the furnace, means to allow escape of products of combustion adjacent the forward end of the upper retort, conveying means in 75 said retorts and means to allow escape of products of distillation.

3. In an apparatus for destructive distillation, the combination of a primary retort, a secondary retort located below said primary retort, a communicating passageway between the said retorts at the rear portions of the same, a furnace inclosing said retorts, a chimney at the forward end of the furnace, a baffle in said furnace between said retorts 85 joined to the front wall of the furnace and terminating adjacent the rear end thereof, means to apply heat to the forward end of said lower retort whereby the degree of heat about said retorts will gradually decrease 90 toward the rear end of the lower retort, and from the rear end toward the forward end of the upper retort, means to introduce material into the forward end of the upper retort, means to discharge material from the 100 forward end of the lower retort and means to permit escape of gaseous products of distillation.

4. In an apparatus for destructive distillation, the combination of a primary retort, 105 a secondary retort located below and in alignment with the primary retort, a communicating passageway between the said retorts at the rear portions of same, a furnace in which said retorts are contained, a 110 chimney for said furnace at its forward end, a horizontal partition in said furnace between said retorts to provide a lower heating chamber and an upper heating chamber there being an opening between said heating chambers at the rear portion thereof, means to so control the heat temperature in 115 said chambers that the heat applied to the secondary retort is of lowering degree toward its rear portion, and the heat applied 120 to the primary retort is of lowering degree toward its forward end, a discharge cavity for the receiving of the carbonized contents of the secondary retort at its forward end, a condensing chamber, a conduit leading 125 from the rearward portion of the primary retort into the condensing chamber to convey the vaporized contents of the retorts into the condensing chamber, means in the condensing chamber to cool said vaporized con- 130

tents, a settling tank for receiving from said cooling means the distillates of said vaporized parts, a valve mechanism for providing a continuous feed of substance under 5 treatment into the forward portion of the primary retort, means operable in said retorts to agitate and shift the cob substance through and from the primary retort and through the secondary retort to the dis-

charge cavity, a suction producing means 10 and power transmitting connections between the conveyer means and valve mechanism, substantially as described.

In testimony whereof we affix our signatures.

CARL A. NOTTINGHAM.
CARL TUHEY.
